UNITED STATES PATENT OFFICE

JOSEPH F. DONAHUE, OF EDGEWOOD, RHODE ISLAND

SHOULDER-STRAP HOLDER

Application filed December 4, 1930. Serial No. 499,954.

This invention relates to a shoulder strap holder, and has for its object to provide a simple construction which may be easily secured to a dress or the like, to prevent the shoulder straps of lingerie or other garments from sliding over the shoulder.

A further object of the invention is the provision of a retaining device for shoulder straps and the like, which may be made of a single piece of stock suitably cut and bent to be mounted upon the garment of the user.

A still further object of the invention is the provision of a member which will have sufficient inherent resiliency to force the prongs or spurs mounted thereon into the garment to hold the same in position.

With these and other objects in view, the invention consists of certain novel features of construction, as will be more fully described, and particularly pointed out in the appended claims.

In the accompanying drawings:

Fig. 1 is a perspective view of a fragmental portion of a dress, lingerie and strap in their desired positions upon the wearer; and showing my improved strap holder for maintaining them in these positions.

Fig. 2 is a perspective view of my strap holder;

Fig. 3 is a section thru the garment, the strap holder and strap extending therethru.

It is found by women in the wearing of lingerie that the shoulder straps for supporting the same often slip from the shoulder to the annoyance of the wearer, and in order that these may be maintained in their desired position, I have provided a simple structure which may embrace the straps and then be secured to the dress of the wearer and held in such position by its inherent resiliency, which securely mounts the same in position and yet provides freedom of movement of the strap or straps therethru to move with the wearer in the various movements of the body; and the following is a detailed description of the present embodiment of this invention illustrating the preferred means by which these advantageous results may be accomplished.

With reference to the drawings, 10 design-

nates the body portion of a strip of sheet stock such as metal, celluloid or other suitable material, which has its end portions 11 folded, as illustrated in Fig. 2, to extend toward each other, generally on the arc of a circle to space them from the body portion 10. Upon each of these end portions, there is mounted a prong 12 which may be conveniently raised from the stock, as illustrated. The prongs are oppositely outwardly directed and each is upwardly inclined to project into the garment. The ends 13 of the member are spaced apart, permitting the member to be sprung inwardly and the spurs 12 positioned in the fabric 14 of the garment which extends over the shoulder, and upon release of this bending-in pressure of the member, the prongs 12 spread apart forcing themselves into the garment and under the pressure due to the inherent resiliency of the stock from which the member is made maintain these prongs in set position.

It will be understood that in the use of the device, the same is placed about the shoulder strap 15 or shoulder straps, if there be more than one, and between the portions 10 and 11, as illustrated in Figs. 1 and 3, before positioning the member on the garment 14, as above mentioned.

When the straps are positioned within and embraced by the member and the member mounted upon the garment, the garment cooperates with the member to close the opening 16 between the ends 13 and thus by completely encircling the shoulder strap 15 forms a loop about the straps and lock the same in place. There is sufficient space between the portions 10 and 11 to permit the straps to freely slide thru the member which may occur due to the movement of the body of the wearer, and yet the straps cannot slip over the shoulder 17 to permit dropping of the clothing which they support, to the discomfort of the wearer.

While I have described certain construction forms which embody the principles of my invention, it is obvious that other desired changes in arrangement, may be made within the spirit and the scope of the invention as defined in the appended claims.

I claim:

1. A shoulder strap holder comprising a strip of sheet stock with blunt ends folded to extend toward each other, and prongs carried by the folded portions to engage a garment and secure the holder in place.
2. A shoulder strap holder comprising a strip of sheet stock with its ends folded to extend toward each other, and outwardly directed prongs adjacent said ends to engage a garment and secure the holder thereto.
3. A shoulder strap holder comprising a body portion of inherent resilient stock, portions spaced therefrom, prongs on said spaced portions for engaging a garment by flexing said body portion to space said prongs a different distance and place them under tension whereby the inherent resiliency of the stock forces the prongs into the garment to secure the body portion in spaced relation thereto.
4. A shoulder strap holder comprising a body portion of resilient stock, end portions spaced therefrom, prongs on said spaced portions located inwardly from the ends and edges thereof for engaging a garment to secure the body portion in spaced relation thereto, said end portions being movable toward each other due to the resiliency of said body to cause the prongs to be under pressure in the garment.
5. A shoulder strap holder comprising a body portion of resilient stock, portions folded thereover and spaced therefrom, outwardly directed prongs on said spaced portions for engaging a garment to secure the body portion in spaced relation thereto.
6. A shoulder strap holder comprising a body portion of resilient stock, end portions folded thereover and spaced therefrom, and prongs raised from the stock of said end portions to engage a garment and secure the body portion thereto.
7. A shoulder strap holder comprising a body portion of resilient stock, end portions folded thereover and spaced therefrom, the ends of said portions being spaced apart, outwardly directed prongs on said spaced portions for engaging a garment to secure the body portion in spaced relation thereto.
8. A shoulder strap holder comprising a body portion, portions secured thereto and overlying the same in spaced relation thereto, and outwardly directed prongs on said portions to engage a garment and secure the body portion thereto.
9. A shoulder strap holder comprising a body portion, portions secured thereto and overlying the same in spaced relation thereto, and spurs on said portions raised from the stock thereof to engage a garment and secure the body portion thereto.

In testimony whereof I affix my signature.
JOSEPH F. DONAHUE.
